UNITED STATES PATENT OFFICE.

LEONARD D. SOUBIER, OF TOLEDO, OHIO, ASSIGNOR TO THE OWENS BOTTLE COMPANY, OF TOLEDO, OHIO, A CORPORATION OF OHIO.

METHOD OF AND APPARATUS FOR FORMING GLASS TUBING.

Application filed October 4, 1923. Serial No. 666,428.

To all whom it may concern:

Be it known that I, LEONARD D. SOUBIER, a citizen of the United States, residing at Toledo, in the county of Lucas and State of Ohio, have invented new and useful Improvements in Methods of and Apparatus for Forming Glass Tubing, of which the following is a specification.

My invention relates to a device for producing glass tubing, and particularly to a device of the type wherein the glass flows from an outlet opening in the bottom of a container and is controlled and formed at said outlet opening.

An object of the present invention is to provide in a tube flowing and drawing device, means to cause the glass as it issues from the outlet opening, to assume the shape of a tube and thereafter be gradually brought to the desired size of tube required.

A further object is the provision of means for circulating the glass at the outlet so that the issuing glass will be of uniform viscosity.

Other objects of the invention will appear hereinafter.

In the accompanying drawings:

Figure 1 is a side elevation of an apparatus constructed in accordance with my invention.

Figure 2 is a part sectional plan of the projecting furnace boot or container.

Figure 3 is a sectional side elevation taken at the line III—III on Figure 4.

Figure 4 is a part sectional front elevation of the device.

A furnace boot or extension 10 is continuously supplied with molten glass 11 from a furnace 12. Projecting upward from the floor of the boot is a wall or dam 13 which is shaped so as to form with the front wall of the boot, a pot 14, said pot having formed in the bottom thereof an opening 15 through which the glass issues.

Projecting vertically downward into the glass, through the opening 15 and concentric therewith, is a clay forming member 16 (Fig. 3) which is shaped at 17 so as to begin the formation of a tube as the glass issues from the outlet 15 and flows down around said portion of the former. The former 16

is mounted in a split clamp 18 which has a screw thread connection with a hollow sleeve 19, said sleeve mounted for rotation in an adjustable bearing sleeve 22. The bearing sleeve 22 is adjustable vertically in 55 a bearing bracket 23 and is held against rotation by a key 24 in said bracket. The means for adjusting the bearing sleeve comprises a worm 25 mounted on the bracket 23 and meshing with teeth 26 on the sleeve. A 60 universal joint 27 connects the adjusting rod 28 to the worm, said rod having at its lower end an adjusting hand wheel 29. The rotation of the said hand wheel adjusts the bearing sleeve 22 up or down, thereby raising or lowering the former 16 to control the quantity of glass passing through the opening 15 of the boot.

Attached to the upper end of the hollow sleeve 19 is a spur gear 31 running in mesh 70 with a pinion 32 mounted on a shaft 33 which projects upward from the bracket 23. A sprocket 34 formed on the lower end of the pinion has a driving connection 38 with a suitable source of power. 75

Extending downward through the hollow sleeve 19 and through the opening 35 of the former 16 is a clay nozzle or blow pipe 36 which serves as a gauge to control the diameter of the tube as it is being drawn and also 80 supplies air, for forming the tube, through a passageway 37 formed therein. Attached to the upper end of the blow pipe 36 is a tubular member 40 having a threaded connection 41 with a worm wheel 42, said member 40 being mounted for vertical adjustment in a bearing 43 formed as part of a supporting bracket 44. A worm 45 on a shaft 46 is in mesh with the said worm wheel and provides a means of adjustment 85 for the blow pipe 36. An adjusting rod 47 (Fig. 4) provided with a hand wheel 48, is connected to the worm shaft by a universal joint 49, thereby bringing the means of adjustment within easy reach of the 90 operator.

A housing 50 (Figs. 1 and 2) entirely surrounds the boot 10 and has openings 51 through which burners 52 are projected to maintain a correct temperature in the boot 100

10. A wall or cylinder 53 (Fig. 3) surrounds the opening 15 and prevents the direct application of flame to the glass, but is so formed with thin portions 54 at certain intervals that the heat will be conducted therethrough and prevent the too rapid chilling of the glass as it emerges from the pot.

A coil 55 is provided beneath the outlet 15 for temperature control at this point. The inflow of molten glass to the pot 14 may be controlled by the adjustable clay block 56, and may also be shut off entirely by lowering to its lowermost position. This control block is suspended by cable 57 from a pulley 58 and adjusted by a screw 61 in a bracket 62 attached to the furnace 12.

In operation, the gate 56 is raised allowing a continuous flow of molten glass to the pot 14. The pinion 32 is driven continuously, thus driving the gear 31 and rotating the former 16, thereby circulating the glass in the pot 14. The glass flows continuously by gravity through the annular passageway between the former 16 and the walls of the outlet opening 15, so that a tubular shape is imparted to the issuing glass. The rotary circulation of the glass tends to retard the gravity flow, thus giving better control. It also imparts an equal temperature to the glass at all points in the circumference of said passageway and, moreover, insures a uniform thickness of the walls of the tube throughout its circumference. By adjusting the former vertically by means of the hand wheel 29, the amount of glass issuing from the outlet 15, and, therefore, the thickness of the walls of the tube is controlled.

40 Now, in order to overcome to a certain extent the action of gravity upon the glass at the drawing point, the blow pipe 36 is held stationary, while the former 16 rotates, and the glass adhering to the stationary blow pipe automatically creates at the drawing point a tension which acts against gravity when the tube is being drawn. Variations in the height to which the blow pipe is adjusted will vary the diameter of the tube formed within certain limits and at the same time vary the amount of tension at the drawing point. The diameter of the tube may also be varied by the use of blow pipes of various diameters. By controlling the application of heat to the walls of the cylinders 53, the temperature at the drawing point may be controlled. The coil 55 is provided for the purpose of giving a chill of sufficient intensity to the tube as formed, in order that it may retain its shape, but is to be used only as conditions at this point require. The tubing may be drawn by any suitable means known in the art.

60 Modifications may be resorted to within 65 the spirit and scope of my invention.

What I claim is:

1. In a tube forming device, the combination of a container for molten glass having an outlet opening in the bottom thereof, a forming device projecting vertically downward into the glass and through said opening, and a blow pipe disposed within said forming device and protruding below the forming device in position to be engaged by the issuing glass and thereby assist in imparting a tubular formation to the glass. 70

2. In a tube forming device, the combination of a container for molten glass having an outlet opening in the bottom thereof, a forming device projecting vertically downward into the glass and through said opening, a blow pipe within and projecting below the said forming device and providing a surface over which the glass flows beyond the forming device, and means to adjust said blow pipe vertically relative to the forming device and thereby vary the size of tubing. 80

3. In a tube forming device, the combination of a container for molten glass having an outlet opening in the bottom thereof, a vertically disposed blow pipe projecting downward through said opening, the lower portion of said pipe providing a shaping surface over which the glass flows after passing the outlet opening, and means interposed between the said pipe and outlet to distribute the glass to said pipe. 90

4. In a tube forming device, the combination of a container for molten glass having an outlet opening in the bottom thereof, a vertically disposed blow pipe projecting downward through said opening, the lower portion of said pipe providing a shaping surface over which the glass flows after passing the outlet opening, and means separate from the blow pipe adjustable to vary the distribution of glass to said blow pipe. 100

5. In a tube forming device, the combination of a container for a pool of molten glass having an outlet opening in the bottom thereof, a vertically disposed blow pipe projecting downward through the glass in the container and through said opening and providing a surface over which the glass flows as it issues from the pool, means to vary the distribution of glass to said blow pipe, and means to vary the diameter of tube drawn. 110

6. In a glass forming device, the combination of a container for molten glass having an outlet opening in the bottom thereof, a forming device projecting downward into the glass and through said opening, a stationary blow pipe disposed within and projecting beyond said forming device, means for continuously rotating the forming device about the axis of the blow pipe, and means to vary the volume of glass passing from said forming device to said blow pipe. 115 125

7. The method of forming glass tubing which consists in causing molten glass to flow vertically downward from a pool of molten glass in the form of a tube and forming said tube at the point of departure of the glass from the pool, and causing a rotary movement of the glass at said point of departure.
8. The method of drawing cylindrical glass which consists in causing molten glass to issue vertically downward from a pool of molten glass in cylindrical form and imparting the cylindrical formation to the glass at the point of departure from the pool, and causing a rotary movement of the glass at said point of departure.
9. The method which consists in causing a rotative movement of glass in a pool of molten glass, and drawing the rotating glass away from the pool in the form of a tube extending vertically downward from the pool and formed at the point of departure from the pool.
10. The method which consists in continuously supplying molten glass to a pool of molten glass, causing a rotative movement of glass in the pool, drawing the rotating glass continuously away from the pool in a cylindrical form extending vertically downward from the pool, and causing said form to be imparted to the glass at its point of departure from the pool.
11. The method which consists in causing a gravity flow of glass in the form of a vertical tube extending downward from a pool of molten glass, and imparting said tubular form to the glass at its point of departure from the pool.
12. The combination of a container for molten glass having an outlet opening in the bottom thereof, a shaping member projecting downward into the glass concentrically with said opening and forming with the opening an annular passageway through which the glass issues, the lower portion of said member extending below the outlet and having a downwardly tapered surface over which the glass flows, means for causing a continuous discharge of glass through said passageway, a forming member, and means to supply air through the center of said forming member.
13. The combination of a container for molten glass having an outlet opening in the bottom thereof formed with downwardly convergent walls, a forming device projecting down into said opening and provided with downwardly convergent walls, the walls of said forming device and said outlet together forming an annular downwardly convergent passageway through which glass issues, means for drawing the glass through said passageway, and means to supply air to maintain the glass in tubular form as it is drawn.
14. The combination of a container for molten glass having an outlet opening in the bottom thereof formed with downwardly convergent walls, a forming device projecting down into said opening and provided with downwardly convergent walls, the walls of said forming device and said outlet together forming an annular downwardly convergent passageway through which glass issues, means for drawing the glass through said passageway, means to supply air to maintain the glass in tubular form as it is drawn, and means for adjusting said forming device up and down and thereby adjusting the thickness of the walls of the drawn tubing.
15. The combination of a container for a pool of molten glass having an outlet opening in the bottom thereof formed with tapered walls, a forming device projecting downward through the pool and into said opening and provided with tapered walls, the walls of said forming device and said outlet together forming an annular tapered passageway through which glass issues in tubular form, means for drawing the glass through said passageway, and means to rotate said forming device about the axis of said outlet.
16. The combination of a container for molten glass having an outlet opening in the bottom thereof, a forming device projecting downwardly into the glass and forming with said outlet a downwardly and inwardly convergent annular passageway for the issuance of glass, means to draw the issuing glass downward in the form of a tube, a blow pipe extending downwardly through the center of and below said forming device and presenting a forming surface over which the glass flows, and means for relatively adjusting said blow pipe and forming device up and down.
17. The combination of a container for molten glass having an outlet opening in the bottom thereof, a forming device projecting downwardly into the glass and forming with said outlet a downwardly and inwardly convergent annular passageway for the issuance of glass, means to draw the issuing glass downward in the form of a tube, a blow pipe extending downwardly through the center of and below said forming device and presenting a downwardly tapered forming surface over which the glass flows, said forming surface being approximately in line with said annular passageway, and means for adjusting said forming device up and down.
18. The combination of a container for molten glass having an outlet opening in the bottom thereof, a forming device projecting downwardly into the glass and forming with said outlet an annular passageway for the issuance of glass, means to draw the

issuing glass downward in the form of a tube, a blow pipe extending downwardly through the center of said forming device and having its lower end protruding below the forming device in position to provide a forming surface over which the glass flows as it leaves said forming device, and adjusting devices for separately adjusting said forming device and the blow pipe up and down each independently of the other. Signed at Toledo, in the county of Lucas and State of Ohio, this 2nd day of October, 1923. LEONARD D. SOUBIER.
